Company, a corporation of Ohio

Application April 11, 1945, Serial No. 587,656

12 Claims. (CL 62—1)

1

This invention relates to a portable apparatus for holding and vaporizing liquefied gasses and more particularly to apparatus for carrying liquid oxygen in aircraft and supplying gaseous oxygen under a desired pressure to a distributing system or consuming device.

Apparatus for storing and vaporizing liquefied gases as customarily employed generally consists of a pressure-resistant vessel for holding a supply of the liquid, which vessel is protected by a surrounding layer of insulation retained within an outer shell. Various means have been employed to effect vaporization of portions of the stored liquid in order to produce gas under a desired pressure and in the quantity required for use. One such vaporizing means comprises an electric immersion type of heater, the current supply to which is controlled by a rheostat. In the operation of such apparatus it is ideally desired that no evaporation of the liquefied gas should occur during periods of no demand for gas. In practice, however, even with best known type of heat insulation some leakage of heat from the surrounding atmosphere into the liquid occurs so that the liquefied gases cannot be stored for an indefinite period and provision must be made for such minimum rate of evaporation.

In a portable apparatus it is desired and often necessary that the apparatus be capable of movement into various positions and particularly in aircraft apparatus it is necessary that the device be operable to supply gas at the desired rate for an adequate period of time even in an inverted position. This requirement imposes unusual problems such as preventing an undue increase of heat leakage when in an inverted position, and of preventing the discharge of liquid through outlets which for normal operation should deliver only gas. Additionally, the apparatus should hold liquid for a required length of time, deliver gas in the quantity required, when required, and at a substantially constant predetermined pressure. It is also preferable that the apparatus should be light in weight, simple to operate and safe. Apparatus for the general type herein described which includes an insulated pressure vessel for holding a supply of liquefied gas and means for effecting control of vaporization of portions of the liquid, is termed a cold converter.

It is, therefore, a principal object of the invention to provide an improved apparatus for holding and vaporizing liquefied gas, to deliver gas in quantities as and when required at a predetermined pressure.

Further objects of the invention are: to provide

such an apparatus which may be held in any position, including an inverted position, while the apparatus continues to hold the liquid without excessive vaporization or vaporizes the liquid and produces gas at a rate required for use; to provide a portable cold converter of the vacuum insulated necked construction, which has a gas chamber arranged in the neck communicating with the liquid-holding space in such a manner as to prevent excessive flow of liquid into the warm end of the neck when the cold converter is in the inverted position; to provide a cold converter having liquid phase and gas phase connections arranged with trapping means to prevent substantially increased vaporization of liquid when the cold converter is tilted or inverted; and to provide a cold converter of the necked construction in which the heat leak through the neck is low.

5 20 These and other objects of the invention will in part be obvious and in part become apparent from consideration of the following description in connection with the accompanying drawings in which:

25 Fig. 1 is a view mainly in vertical cross-section of an exemplary cold converter construction embodying the invention.

Fig. 2 is a plan view of the cold converter shown in Fig. 1.

30 Fig. 3 is a sectional view of a cold converter illustrating particularly an alternate form of gas phase trap and;

Figs. 4, 5, and 6 are fragmentary sectional views illustrating still other arrangements of the gas 35 phase trap.

Referring to the drawings and more particularly to Fig. 1, the cold converter includes an inner vessel 10, which may have any suitable shape, the spherical shape as illustrated being 40 generally preferable. The vessel 10 is made strong enough to withstand safely a predetermined working pressure, which working pressure is the pressure under which gas is delivered from the converter. The cold converter is preferably 45 provided with a vertically extending neck 11, secured at its upper end to a head block 12. A gas discharge conduit 13 is connected to the head block 12 to communicate with the interior of the neck 11. The upper end of the neck 11 is closed 50 by a removable plate 14, which is secured gas tightly against the upper face of the head block 12. From the plate 14, there extends a tube 15, downwardly through the neck 11 into the liquid holding space of the vessel 10. The tube 15 carries at its lower end an electric immersion type

of heater 16. The electric wires for supplying energy to the heater extend through the tube 15 and pass through an insulating bushing 17 in the plate 14. From the bushing 17, the wires 18 pass through an electric conduit 19 which is secured to the top of the plate 14.

The space between the wall of the neck 11 and the tube 15, forms a gas chamber 20 which is closed at its upper end by the plate 14, and at its lower end by an annular member 21. The lower end of the neck 11 extends within the vessel 10 a short distance and is provided with an internal shoulder 22 against which the annular member 21 forms a seal. The annular member 21 extends around the tube 15, and is slidable thereon so that it can be urged against the shoulder 22 by a spring metal bellows 23, which surrounds the tube 15 and is gas tightly secured at its lower end to the annular member 21, and at its upper end to the tube 15. Thus when it is desired to remove the heater 16 and tube 15, it is merely necessary to loosen the plate 14 and withdraw the assembly. When the heater assembly is inserted and the plate 14 secured in place, the bellows 23 will be compressed so that it urges the annular member 21 against the shoulder 22, and a sealed chamber 20 is thus obtained.

Gas phase communication between the vessel 10 and the gas chamber 20 is maintained through a trapped conduit 24. The conduit 24 has an inlet opening 25 at a point near the top of the gas space in the vessel 10, and is formed to have a convolution 26 substantially in the horizontal plane. The conduit 24 also has a convolution or loop 27 substantially in a vertical plane, and the remaining end 28 is secured to the portion of the neck 11 that extends within the vessel 10 so as to open into the chamber 20. The chamber 20 thus is provided with a universally trapped connection with the gas space of the vessel 10.

The vessel 10 is enclosed within a suitable heat insulating means which may be one of several customary types of insulation. For a light weight vessel the vacuum type of insulation may be preferable. To this end there is provided an insulating jacket or shell 30 which is spaced from the outer wall of the vessel 10 to provide an insulating space 31. The space 31 is evacuated to a high degree and both the outer surface of the vessel 10 and the inner surface of the jacket 30 are highly polished to reduce heat radiation. Jacket 30 also has an extension 32 around the neck 11, and the upper end of such extension is secured to the head block 12 in a gas tight manner, such as by welding.

The entire container is supported by a suitable frame such as a surrounding cylindrical shell 33 having an upper conical portion 34 which is secured to the head block 12. It will be seen, therefore, that the inner vessel is suspended by its neck 11 from the head block 12, that the outer jacket 30 is independently suspended from the head block 12, and the head block 12 is carried by the conical portion 34 on the shell 33. The lower edge of the shell 33 is provided with a rim or flange 35 which may be employed to secure the converter to the floor of a vehicle or to a portion of an airplane.

The converter is also provided with means for filling the vessel with liquid and discharging liquid therefrom. Such means may be in the form of a conduit 36 which extends into the vessel 10 and passes through the insulation space 31 to the head 12, to which it is secured in a manner to communicate with a passage 37 therein into

which a pipe 38 is secured. A stop valve 39 preferably connects the pipe 38 with a filling connection 40. The liquid phase conduit 36 is also universally trapped by having therein a loop 41 in a vertical plane preferably disposed within the vessel 10, and a plurality of loops or convolutions 42 substantially in a horizontal plane, the loops 42 being preferably disposed in the vacuum space between the neck 11 and the extension 32, and encircling neck 11. The convolutions 42 not only provide a trap substantially in the horizontal plane, but also serve to increase the length of the conduit 36 between the point where it leaves the vessel 10 and the head 12 which latter is warm. Such increased length substantially reduces the conduction of heat through the metal walls of the conduit 36.

Means for measuring the quantity of liquid in the vessel 10 are usually also provided. Such means may be of two types, for example, the trycock and the liquid level gauge types. For the liquid level indicating trycock, a small tube 43 is provided having an inner end 43' located within the vessel 10 at a desired level. The tube 43 is also universally trapped by having a loop 44 in the vertical plane and convolutions 45 in the horizontal plane disposed about the neck 11. The tube 43 passes through the insulating jacket preferably at the head 12 and is connected to a trycock 46 (Fig. 2). Connections for a customary type of liquid level gauge 47 are similarly provided. The low pressure side of such liquid level gauge 47 may be connected to the gas chamber 20 by a connection 47' similarly to conduit 13. The high pressure connection for the liquid level gauge is provided by a tube 48, which passes through the insulating jacket to a point near the bottom of the vessel 10 wherein it is secured gas tightly with its open end in communication with the interior of a small cap 50. The cap 50 has its rim secured to the interior wall of the vessel 10 and is provided with one or more openings 51 adjacent to the wall of the vessel 10.

In operation, a charge of liquefied gas is forced in at the connection 40 while the valve 39 is open. The trycock 46 at the end of the tube 43 is also open and the gas conduit 13 preferably would be open to the atmosphere through a valve 13' therein, although if it is desired to save the oxygen vapors, the valve 13' may be connected to a low pressure gas receiver. As the liquid level rises in the vessel 10, that level at which the end 43' of the tube 43 is positioned will be reached and such occurrence will be indicated by a blow 55 of liquid from the trycock 46. At this time the valve 39 is closed and the valve 13' for venting the gas conduit 13 as well as the trycock 46 are also closed.

If it is desired to put the converter into immediate use for supplying gas, the electric heater will be connected at a socket 19' on the conduit 19 to a source of electric current. The heater causes sufficient vaporization to bring the pressure up to working pressure, after which a pressure control 60 52 connected to conduit 13, operates to regulate the current supply so that the rate of heating and vaporization correspond to the rate at which gas is withdrawn through the gas conduit 13. The working pressure usually is that which it is desired to maintain in the gas distributing or using apparatus, for example, the oxygen distributing manifold of an airplane which may operate at a standard pressure of 400 p. s. i. or a lower pressure such as 65 p. s. i. If gas under pressure is not required immediately after filling the converter

with liquid, the socket 19' is left disconnected and the converter may be allowed to stand with all valves closed for a considerable period of time before normal heat leak from the atmosphere to the vessel 10 is sufficient to heat the liquid and vaporize enough of the liquid to bring the pressure up to the working pressure. If, after the pressure has reached working pressure, no gas is consumed, continued heat leak from the surroundings will cause evaporation to occur at a low rate and tend to further increase the pressure. Therefore, in order to avoid the occurrence of an excessive pressure, a safety relief valve 53 (Fig. 2) is customarily provided and such valve is preferably arranged to communicate with the gas chamber 20 through a connection 53'.

If the converter is positioned up-side-down, the vertical loop 41 in the conduit 36 forms a trap that prevents flow of liquid through the conduit 36 toward the head 12, particularly since the conduit 36 is dead-ended by the valve 39. For example, some liquid will ordinarily stand in the lower part of the tube 36, and when the converter is inverted a small portion of such liquid may flow past the loop 41 and enter the warmer portions of the coils 42 wherein it vaporizes. A dead ended pocket of gas however results in the portions of conduit 36 between the trap loop 41 and the valve 39 which prevents further flow of liquid over the high point of the trap 41 and a liquid level will stand in the trap. The loop 44 in the tube 43 operates in a similar manner.

The normal gas phase trap inlet 25, will be submerged in liquid when the converter is up-side-down but such liquid will be prevented from rising through the tube 24 by gas pressure in the gas chamber 20 and tube 24 due to the loop portion 27 in the vertical plane. If, however, gas is withdrawn through the gas conduit 13, liquid will rise in the loop portion 27 until some of it flows over the bend. Such liquid that flows over the bend will fall through the gas chamber 20, and eventually come in contact with the head 12. The head 12 is relatively very hot being substantially at atmospheric temperature so that any liquid that reaches it will be immediately vaporized. Such vaporization restores the pressure in the chamber 20, which pressure serves to prevent excessive liquid from flowing over the bend of the loop 27. It will be seen then that only that amount of liquid which is needed to produce the gas that is withdrawn through conduit 13 will flow into the gas chamber 20.

Operation in the up-side-down position will occur for an appreciable and desired length of time because the head 12 is relatively massive and the metal from which it is constructed contains an appreciable store of heat. Furthermore, heat is continually absorbed by the head 12 from the atmosphere. The head 12 thus functions as a heat reservoir for operation of the converter when in the up-side-down position.

When the converter is placed in a position lying on its side, for example, the traps or trap loops 42, 45 and 26 become operative to prevent flow of liquid through the conduits 36, 43 and the trapped conduit 24, because such trapping convolutions are now in the vertical plane. If the trap inlet 25 is below liquid level when the converter is on its side, a supply of gas at the desired pressure may be still obtained through the conduit 13, because the trap and gas chamber 20 will function substantially as described in the up-side-down position. If, however, the inlet 25 is in the gas space above the liquid level, the converter will function

to produce gas in the normal manner as described when it is vertical.

The gas phase chamber and trap assembly may have various forms as illustrated, for example, in Figs. 3 to 6. Referring to Fig. 3 particularly, the inner vessel 110 is surrounded by an insulating space 131, which may be filled with a comminuted or powder insulating material held within an outer jacket 130. The vessel 110 has a neck 111, which extends to the upper end of the jacket 130 and is suspended therefrom. In this embodiment a unitary gas chamber and heater insert assembly is provided. The insert assembly comprises a tube 54, having upper and lower heads 55 and 56. The upper head 55 is provided with a flange 57 that is secured gas tightly to a corresponding flange 58 at the upper end of the neck 111. The lower end of the tube 54 enters the vessel 110 a short distance and is placed in gas phase communication with the interior of the vessel 110 by a trapped connection 124 disposed entirely within the gas chamber 120 in the tube 54. The lower end of the connection 124 passes through the wall of the tube 54 and opens into the vessel 110. The connection 124 is provided with one or more loops or convolutions 126 in the horizontal plane and a loop or convolution 127 in the vertical plane, thus providing trapping in any position. The heater tube 115 passes gas tightly through the heads 55 and 56 to which it is secured. The gas discharge conduit 113 preferably passes through the head 55 and extends within the gas chamber in the tube 54 a short distance, which has the advantage that liquid cannot blow out through the conduit 113 during operation in the up-side-down position.

In Fig. 4 the gas phase trap 224 is also disposed within the gas chamber 220 but the arrangement differs from that of Fig. 3 by having the trap tube 224 rise vertically to a loop 227 disposed in the vertical plane and then be formed with a loop or convolutions 226 disposed in the horizontal plane below the loop 227.

In Fig. 5 a gas chamber 320 within the converter neck 311 is formed by a partition 59 near the joint between the neck 311 and the vessel 310. The trap connection 324 is provided with an inlet 325 near the top of the vessel 310 with horizontal loops 326 and with a vertical plane loop 327 below the loops 326. The outlet end of the connection 324 passes through and is secured to the partition 59.

In the embodiment shown in Fig. 6, the inner vessel 410 has a vertical extending neck 411, and a combined heater and gas chamber assembly 60 is employed. The assembly 60 comprises a relatively long tube 61 that extends through the neck 411 to a point near the bottom of the vessel 410. The tube 61 is closed at the bottom and a heater element is preferably disposed therein near the bottom. At a point near the top of the vessel 410 the tube 61 is provided with a transverse partition 62 to which is secured a heater conduit 63, through which the electric wires for the heater may pass. Just above the partition 62 are openings 64 in the wall of the tube 61. To form a part of the desired gas chamber, a cup-shaped sealing member 65 is provided which is welded gas tightly to the upper part of the vessel 410, and has a bottom 66 having a central hole 67 through which the tube 61 passes. The bottom 66 is just below the openings 64. The hole 67 fits the tube sufficiently closely to provide a sliding fit so that no appreciable

amount of liquid will pass through the clearance space when the converter is in the up-side-down position. The gas chamber is thus formed by the space within the member 65, the space between the tube 61 and the heater conduit 63 and the space between the tube 61 and the wall of the neck 411. The gas phase connection between such gas chamber and the vessel 410 is provided by the connection 424 which has an inlet 425 near the upper part of the vessel 410 outside of the member 65 and which is provided with horizontal loops or convolutions 426 and a vertical loop 427. The remaining end of the connection 424 enters gas tightly through member 65 to communicate with the gas chamber.

The operation of the alternative forms of gas chamber and trapped gas phase connections as shown in Figs. 3 to 6 inclusive, is substantially the same as described in Figs. 1 and 2. An important path for heat leakage to the liquid holding vessel is through the metal of the neck. Although lengthening the neck reduces such heat leak, it is usually essential to make the neck as short as possible in order that the converter shall be no higher than space requirements in an airplane permit. At the same time the converter must have a required liquid holding capacity. For these reasons it will generally be preferable to have a minimum of metallic paths for heat conduction down the neck, thus when the neck is to be short, it is more advantageous to employ a construction in which the gas chamber within the neck is formed by the neck walls as in Fig. 1 and is not within an inserted assembly as in Figs. 3 and 6. The inserted assembly construction however has the advantage of making it unnecessary to provide a liquid filling connection because the converter can be filled with liquid through the neck while the insert assembly is removed and when it is desired to put the converter into operation the heater assembly may be inserted and secured in place.

Although several embodiments of the invention are disclosed in detail, it is contemplated that numerous changes may be made in such details without departing from the principles of the invention, for example, although an electric heating means has been shown, a heating means of the type employing a heated fluid may be substituted or a heating means external of the inner vessel may be employed and, although the converter has been described particularly for the conversion of liquid oxygen to provide gaseous oxygen, it is to be understood that similar apparatus can be employed for gasifying other liquefied gases.

What is claimed is:

1. A gas dispensing apparatus comprising an inner vessel for holding a body of liquefied gas; a heat insulating jacket surrounding said vessel having an outer shell; and conduit means extending from within said inner vessel through said heat insulating jacket to a point externally of said outer shell, said conduit means having a plurality of complete convolutions, at least two of which lie respectively in planes which are substantially perpendicular to each other and define a continuous passageway, said convolutions being disposed internally of said outer shell to prevent gravitational flow of liquid through said conduit means in any and all positions of the apparatus.

2. An invertible gas dispensing apparatus comprising an inner vessel for holding a body of liquefied gas, a heat insulating jacket surrounding said vessel having an outer shell; and a gas phase

passage means for conducting gas material from a point normally near the top of said inner vessel to a point externally of said outer shell, said passage means comprising a gas chamber having a warm end spaced from said inner vessel, a cold end adjacent said inner vessel, at least the major part of said gas chamber including its cold end being within said insulating jacket, a gas discharge connection at said warm end, and a restricted connecting means providing communication between said cold end portion of the gas chamber and the normally gas phase space of said inner vessel.

3. An invertible gas dispensing apparatus comprising an inner vessel for holding a body of liquefied gas; a heat insulating jacket surrounding said vessel; and a gas phase passage means for conducting gas material from a point normally near the top of said inner vessel to a point externally of said jacket, said passage means including a gas chamber having a warm end and an inner end adjacent said inner vessel, at least the major part of said gas chamber including its inner end being within said insulating jacket, and a trapped connection providing communication between the inner end portion of said gas chamber and the normally gas phase space of said inner vessel.

4. A gas dispensing apparatus according to claim 3 in which said trapped connection comprises a tube having portions disposed substantially in planes which are perpendicular to each other.

5. A gas dispensing apparatus according to claim 3, in which said trapped connection is disposed entirely within said inner vessel.

6. A gas dispensing apparatus according to claim 3 in which said trapped connection is disposed entirely within said gas chamber.

7. A gas dispensing apparatus according to claim 3 in which said inner vessel is provided with an extending neck portion, said gas chamber is disposed with said neck portion on the major part of which is within said insulating jacket, and the warm end of said gas chamber is in heat exchange relation with a heat reservoir at the outer end of said neck portion.

8. In a portable cold converter of the type having an inner vessel for holding liquefied gas surrounded by a heat insulating jacket; a liquid conduit means; a gas phase conduit means; and a liquid level indicating conduit means; each of said conduit means having an open end within said inner vessel and passing through said insulating jacket to an external point; and traps in each of said conduits arranged to prevent gravitational flow of liquid through said conduits in any and all positions of said converter including the up-side-down position.

9. In a portable and invertible cold converter of the type having an inner vessel for holding liquefied gas surrounded by a heat insulating jacket; a neck extending outwardly from said inner vessel, said neck being secured to a head at its outer end; a gas chamber in said neck having an outer end closure connectable to said head and an inner end closure, at least the major part of said gas chamber being protected from atmospheric heat by said insulating jacket; a heater element having a heatable portion within the liquid space of said inner vessel, and a conduit portion extending through said gas chamber and said end closures; a gas discharge connection at the outer end of said gas chamber; and means providing restricted gas phase communication be-

tween said gas chamber and the normally gas containing space of said inner vessel.

10. In a portable and invertible cold converter of the type having an inner vessel for holding liquefied gas surrounded by a heat insulating jacket; a neck extending outwardly from said inner vessel, said neck being secured to a head at its outer end and the remainder of said neck being disposed within the insulating jacket, said neck also having an internal shoulder adjacent its inner end; a removable heater element having a heatable lower portion within said inner vessel, a conduit portion extending through said neck and means at its upper end for securing said element to said head; a yieldable sealing means carried by the conduit portion of said element in sealing engagement with said shoulder in the neck for forming a gas chamber within said neck, means providing gas phase connection between said gas chamber and the inner vessel; and a gas discharge connection at the outer end of said neck for discharging gas from said gas chamber.

11. In a portable and invertible cold converter of the type having an inner vessel for holding liquefied gas surrounded by a heat insulating jacket; a tubular neck extending outwardly from said inner vessel, said neck having a head at its outer end and the remainder of said neck being disposed within the insulating jacket; and an insert assembly through said neck, said insert assembly comprising a tubular gas chamber having upper and lower end closures, means for gas tightly securing the upper end of said chamber to said head, a gas discharge connection from the upper portion of said gas chamber, an elongated heater element having a conduit portion passing longitudinally through said gas chamber and gas tightly through said end closures and a heater portion disposed within the liquid holding space of said inner vessel, and a liquid trapping connection providing gas phase communication between the lower portion of said gas chamber and the gas phase space of said inner vessel.

12. In a portable and invertible cold converter of the type having an inner vessel for holding liquefied gas surrounded by a heat insulating jacket; a tubular neck extending outwardly from

said inner vessel, said neck having a head at its outer end and the remainder of said neck being disposed within the insulating jacket; and an insert assembly through said neck, said insert assembly comprising a tube having at its upper end an end closure and means for securing it gas tightly to said head and a transverse partition or closure adjacent the joint between said neck and the inner vessel, a heater element conduit in said tube and passing gas tightly through said upper end closure and said partition, a heater portion below said partition extending within the liquid holding space of said inner vessel, a cup member within said inner vessel having a rim secured gas tightly to the upper inner wall of said inner vessel and having a bottom with an opening through which said tube passes, said cup member forming an annular chamber about said tube having a close sliding fit in said opening to prevent excessive liquid flow therethrough, an opening in the wall of said tube providing communication between said annular chamber and the interior of said tube above said partition and a liquid trapping connection providing gas phase communication between said annular chamber and the gas space of said inner vessel.
